UNITED STATES PATENT OFFICE.

MELVILLE E. PETERS, GEORGE H. FATH, AND ALBERT F. MILLER, OF DENVER, COLORADO, ASSIGNORS TO THE PETERS PATENT RIGHTS COMPANY, OF DENVER, COLORADO, A CORPORATION OF COLORADO.

APPARATUS FOR WRAPPING EXTENSION-EDGE BOXES.

1,244,539.

Specification of Letters Patent. Patented Oct. 30, 1917.

Application filed September 25, 1916. Serial No. 122,060.

To all whom it may concern:

Be it known that we, MELVILLE E. PETERS, GEORGE H. FATH, and ALBERT F. MILLER, citizens of the United States of America, 5 residing at the city and county of Denver and State of Colorado, have invented a new and useful Apparatus for Wrapping Extension-Edge Boxes, of which the following is a specification.

10 Our invention relates to a new mechanism for wrapping extension edge boxes in box wrapping machines, and the objects of our invention are:

First, to provide mechanism for covering 15 and wrapping the extension edge portion as well as other parts of paste board boxes with blanks or labels made of calendered or other finished surfaced paper or with other suitable box covering or wrapping materials.

Second, to provide a simple, quick and positively combined box bottom extension edge and box end wrapping mechanism.

Third, to provide a box bottom extension 25 edge and upper box surface blank wrapping and gluing mechanism, in which two separate wipers are arranged to move simultaneously together to wrap the blank against the surfaces of the extension edge and upper portions of the box and to then wrap the blank ends against the upper surfaces of the box independent of and while the ends of the blank are being held down against the extension edge of the box by one wiper, and in 30 which the upper wipers back off and return to and connect with the extension edge wiper and they move away from the box together and simultaneously.

We attain these objects by the mechanism 40 illustrated in the accompanying drawings, in which:

Figure 1 is a vertical longitudinal sectional view through a portion of a box wrapping machine embodying mechanism 45 constituting the present invention.

Fig. 2 is an end view of a portion of the machine showing the operating lever for the upper box form or plunger.

Fig. 3 is a side elevation of one of the 50 end wipers in a vertical position showing the extension presser blade in position to press the blank over the extension ends of the bottom of the box.

Fig. 4 is an end elevation of Fig. 3.

Fig. 5 is an edge view of the upper portion of one of the wiper operating rack bars. 55

Fig. 6 is a top view of the supporting slide block for the wiper head, showing the extension presser blade secured thereto.

Fig. 7 is a plan view of one of the supporting standards and mechanism carried thereby for folding the end portions of the side members of a wrapper around and over the ends and corners of a box. 60

Fig. 8 is a central, vertical, sectional view 65 through the mechanism shown in Fig. 7.

Fig. 9 is a side elevation of a portion of the mechanism shown in Fig. 8.

Fig. 10 is an end view of the cross head 70 which carries the side wipers and also the mechanism which effects the side extension folding and pressing operation, the latter mechanism being removed.

Fig. 11 is a side elevation of the cross 75 head shown in Fig. 10, one of the supporting cylinders for the side extension mechanism being shown in section.

Fig. 12 is a front elevation of the mechanism for performing the side extension 80 folding operation.

Fig. 13 is a fragmental plan view 85 showing the cam and levers operated thereby for operating either the ordinary tight wrap mechanism or that for performing the extension bottom work.

Fig. 14 is a horizontal sectional view on the line 14—14 of Fig. 4.

Fig. 15 is a front view showing the stop for limiting the inward movement of the end wipers, and 90

Fig. 16 is a plan view of one of the extension bottom blanks or wrappers, showing a box in dotted lines.

Similar letters of reference refer to similar parts throughout the several views. 95

Referring to the drawings:

The numeral 1 designates a supporting frame which comprises a base plate 2, side frames 3 and a table portion 4. A suitable driving shaft 5 is journaled longitudinally 100 of the frame in suitable bearings 6, that are secured to the base plate of the machine centrally between the side frames 3.

This shaft is adapted to be rotated by any suitable rotative power transmitting mechanism, which we do not illustrate. 105

Upon this shaft we secure disks 7, 8, 9, and 10, the sides of which are provided with

cam grooves or runways in which rollers project that are mounted on levers or rock arms that operate mechanism that is positioned above, below and adjacent to said table and side frames, as will be presently described.

Through the center of the table portion 4, of the machine an aperture is formed, in which a vertical plunger bar 11 is reciprocally mounted in adjustable slideway bearings 12, that are attached to the upper side of the table portion 4 of frame. The lower end of this bar is connected to the upper end of a cam fork 13, having a roller 14 which engages the runway of the cam disk 9 that is secured on the main driving shaft 5 of the machine. The upper end of the plunger bar 11 is provided with a flange 15, that is secured to a block of wood or other suitable material 16 that is made of the size and width of the bottoms of the particular sizes of box that are to be pressed against it. The top surface of this block is covered with a metal plate 17 having a cushion of felt 18, or other suitable material, against which the bottoms of the boxes rest. Our box supporting plungers and our box wrapping side and corner mechanism will partially cover or wrap boxes of from about 3 inches long by one inch wide by one-half inch deep, up to boxes of about 14 inches long by 8 inches wide by 3 inches deep, but each different size of box must have upper and lower plunger blocks that will fit, in the case of the lower plunger, its outside bottom length and width dimensions, and an upper plunger that will fit snugly inside of each sized box the machine will wrap. Each gummed blank that is fed to the wrapping machine rests centrally on top of the lower block, and each box is fed by the upper plunger to rest centrally on the blank and to rest also centrally on top of the block, which forms a movable support for the blanks and the boxes.

Above this lower plunger block and in vertical axial alignment with it, an upper plunger bar 19 is reciprocally mounted in suitable slideway bearings 20, that are formed in an overhanging bracket arm 21, which is secured to the box frame of the machine. The lower end of this plunger bar 19 is provided with a block 22, which we term a box form, and it is made enough smaller than the box and the block of the lower plunger to fit snugly inside of the boxes.

The boxes are fed automatically centrally over the top of the blanks and in that position the upper plunger or box form 22, descends directly into the box against its bottom and presses the bottom of the box down tight against the blank and against the top of the lower plunger block. The lower plunger with its block reciprocates vertically a short distance and the position in which the lower

plunger block first receives the blank and the box shell is the highest point of its vertical reciprocal movement. Consequently when the upper plunger form descends into the box against its bottom, it instantly presses it and the blank against the block of the lower plunger, which forms an abutment to the pressure of the form of the upper plunger of sufficient resistance to glue the bottom of the box to the gummed surface of the blank upon which the box rests.

The lower plunger is then drawn down by its cam 9, and is forced down between the side wipers 43, and as these two plungers move down together the upper plunger which is arranged to move slightly faster than the lower plunger, bears and consequently crowds down against it and thus holds the bottom of the box with a constant pressure against the top of the lower plunger, and as the lower plunger moves slower on its down stroke than the upper plunger, in order to yield to the slower down movement of the lower plunger, the upper plunger is provided with a coiled spring 24, which is mounted on a bolt 25. This bolt is provided with an eye 26, that is screwed upon the upper end of the bolt. This eye 26 is loosely mounted on a stud bolt 27, which is threaded into the side of the reciprocal plunger bar 19. The opposite end of the spring provided bolt is provided with a pin 28, against which a washer 29 bears, and the spring 24 is mounted on the bolt and bears resiliently at one end against the washer 29 and at its opposite end against the underside of one end of an eye bolt 30, that is loosely mounted on the bolt 25 and which is held under adjusted tension on the bolt by two nuts 31, which are screwed down against the eye bolt and enough farther to cause the eye bolt to compress the spring until the eye bolt and the reciprocating plunger bar are under the desired tension. The eye bolt is provided with a threaded stud portion that extends loosely through and is secured by a nut to a lug that forms the terminal end of a lever 32, the opposite end of which is pivotally secured to a yoke 33, that is formed on an arm portion 34 of a yoke shaped frame 35, which rests on and is bolted to the top table portion of the box-shaped supporting frame of the machine.

The lever 32 is reciprocated vertically by a rod 36, one end of which is provided with a yoke lug 37, which straddles the lever and a pivotal bolt 38 is extended through both the lug 37 and the lever. The lever has an elongated slot 39, and the bolt 38 carries a roller 40, which engages the edges of the slot, as the lever is raised and lowered, the said slot permitting the vertical movement of the rod 36, as will be understood. The opposite end of this rod 36 is connected to a lever 41 which is arranged to be en-

gaged by the cam 42, that is formed on the disk 7 which is secured on the main driving shaft.

Each blank fed to the wrapping machine is wrapped against and glued to the opposite sides of each box, side by side, and the oppositely arranged side wipers 43 that turn the upper ends of the sides of the gummed blanks up against the boxes are mounted on two stationary cross head brackets 44, that are secured to the top of the table portion of the frame, and they are arranged on opposite sides of the box supporting plungers 16 and 22. These side wipers preferably consist of pieces of wood, the blank engaging faces of which are covered with strips of felt 45 or other suitable material which is glued or is otherwise secured to each wiper. These wipers are removably secured to projections 46, that are formed on the cross heads 47, that are slidably mounted in slideways 48 that are formed in the brackets 44. There are two of these brackets, one on each side of the upper and lower plungers, and these two plungers reciprocally carry each box and blank between these side wipers. These side brackets are positioned parallel with the longitudinal length of the box wrapping machine, and are secured to the top of the table portion of the frame. These brackets we term the side cross head brackets. These brackets have a central standard portion 49, and two laterally extending wing portions 50. They each support one side and two end wrapping mechanisms. The underside of each cross head 47, is provided with a gear toothed rack portion 51, which is engaged by a toothed segment portion 52, that is formed on one end of a rock arm 53. These rock arms are pivotally secured to the brackets 44, and their opposite ends are provided with pivotal eye bolts 54, through which vertically positioned rods 55 pass loosely. A collar 56 is secured on each rod by a set screw and an expansive spring 57 is mounted on the rod between the collar and the eye bolt 54. The upper end of each rod is threaded and a collar 58 is pinned to it, which engages the eye bolt 54 on the downward movement of the rods 55.

The rods 55 extend down through bosses 59, on the brackets 44, and through the table and rest on the ends of a bar 60, the central portion of which is secured to a vertical plunger 61, that is reciprocally mounted in a slideway formed in a transverse bracket 62, that is bolted to the sides of the frame. The lower end of the plunger bar 61 is connected by a link 63, to one end of a lever 64, the opposite end of which is rigidly secured to a shaft 65, which is mounted in a bearing standard 66, which is bolted to the bed plate. On the shaft

65 are also mounted the outer ends of lever arms 67 and 68, the inner ends of which are provided with rollers, which enter respectively cam grooves in the opposite faces 69 and 70 of the cam disk 8, mounted on the cam shaft 5. Between the arms 67 and 68, and also mounted on the shaft 65, are integrally connected short arms 71 and 72, the inner ends of which are provided with holes which are in line with corresponding holes in the arms 67 and 68. A hand lever 73, is mounted on the hub portion of the arms 71 and 72, and its forward end is pivotally attached to a locking pin 74, which is slidably mounted in the inner ends of the short arms 71 and 72. The locking pin is of such a length that when the lever 73 is shifted in the direction of the arrow, the said pin projects through the hole in the arm 72, and into the hole in the arm 68, thus locking the arms 68, 71 and 72 together, while the arm 67 is disconnected from the arms 71 and 72. The arm 67 and its actuating cam face 69, operate in connection with boxes of the ordinary type, while the arm 68 and its actuating cam face 70, operate in connection with boxes having extension bottoms, the respective cam grooves being arranged to that end. Thus when boxes of the usual type are being covered, the arm 68 is not needed, and when extension bottom edge boxes are being covered, the arm 67 is out of commission. Therefore, when boxes of the usual type are being covered, the short arm 71, which with the arm 72 is rigidly secured to the shaft 65 by a pin or other suitable means, is locked to the arm 67, and when the arm 67 is operated by its cam 69, a corresponding movement is imparted to the short arm 71, which is locked to the arm 67 by the pin 74, and as the arm 71 is rigidly connected to the shaft 65, the said shaft is turned thereby, and the arm 64, which is also rigidly attached to the shaft 65, is rocked, and movement is thus transmitted to the plunger arm 61, through the medium of the link 63. The arm 68 will be rocked by its cam 70, but it will perform no function, as it is not locked to the shaft 65. Collars 75 are secured upon the lower portions of the rods 55, and between these collars and the lower ends of the bosses 59 are interposed coiled springs 76, which act to depress the rods 55, after they have been raised and then released by the cross bar 60.

The vertical movement of the rods 55 causes their collars to compress the springs 76 and raise the rock arm 53, which causes the toothed ends of the rock arms which engage the rack bar 51 of the cross head 47 to move the wiper blocks against the sides of the blank and box, and hold it there with a resilient tension, as the rods 55 are free to move through the eye bolts 54, after

the side wiper is against the box. Consequently the side wipers bear against the box with a resiliently yielding pressure.

The side wipers as above described are used for wrapping box shells in a manner known as tight-wrap work, and we have described it in detail, as our machine has to be changed from the tight wrap kind of wrapping to the extension edge kind of wrapping, and vice-versa. Our present invention, however, applies essentially to wrapping boxes having extension bottom edges and in order to accomplish the wrapping of the extension edges of the opposite sides of the boxes the following additional mechanism is added to the side wipers. The sliding block of each wiper mechanism is provided with a pair of horizontally positioned cylinders 77, that depend from it. These cylinders are provided with solid head portions at one end and have nuts 78 threaded into them at their opposite ends. Axial apertures are formed through the heads and nuts in which stems 79 are reciprocally mounted, and expansive coiled springs 80 surround the stems. The stems are provided with shoulders in the cylinder against which washers 81 rest that receive the thrust of one end of the springs 80, when the stems are moved back through the cylinder by mechanism that is attached to their front ends, and the springs move the stems out forwardly by their expansive tension when the stems are released from backward pressure. A nut is threaded to the outer end of each stem, by which the tension of the spring can be regulated as desired. The outer ends of each pair of stems are threaded into a clip 82 (see Figs. 7, 8, and 11), that is provided with a transverse pin 83, upon which is mounted a horizontal rock plate 84, having a depending bifurcated arm 85, in which is mounted a roller 86. This roller is designed to be engaged by one end of a rock arm 87, which is pivotally secured intermediate of its ends to a support 88, which is bolted to the inner face of the bracket 44. The opposite end of the rock arm is connected to a spring 89, which is attached at its opposite end to a pin 90, projecting from the bracket 44. Plate 84 has a forwardly projecting blade 91 secured upon its upper face. The pin 83 has a surrounding coil spring 92, one end of which engages the clip 82, while its outer end enters a collar on the end of the pin 83. This spring normally holds the blade and its supporting plate 91, tilted upwardly, in which position it is moved against the box and over its extension lip. As the cylinders 77 move inward with the blocks 47, the roller 86 engages the arm 87 and the plate 84 is tilted, and the blade 91 engages the blank and presses it down against the extension portion of the

box, the spring 89 affording a compensating movement for the blade against the box, the blades yielding backwardly from it, when the cylinders and the block continue slightly farther toward the box to complete their stroke. This arrangement allows the blade to engage the box with a resilient pressure. The roller 86 engages the rock arm 87 as the cylinder moves forward and tilts the plate and its blade downwardly against the tension of the spring 89, so that the blade exerts a downward pressure on the extension lip X of the box Y.

Inasmuch as the terminal ends X¹ of the side flaps have to be wrapped around and glued to the corners of the box after the sides and their extension edge treatment has been completed; the next step treatment of wrapping the blank around the box in tight wrap work is performed by the corner wipers. These corner wipers are used to wrap the end portions of the sides of the blank around the corners of the box, as shown in Fig. 7, just before the end wipers move into action to wrap the ends of the label against the ends of the box. There are two of these corner wipers for each end of the box, one at each corner, and they each consist of a plate 93, which is provided with lugs 94, which are pivotally secured to a block 95 by a pin 96. This pin is extended beyond the lugs and a coiled spring 97 is mounted on it, one end of which is secured to a collar on the lower end of the pin, and the other end of the spring is secured to the adjacent lug 94. Each block 95 is tiltingly secured to the end of a toothed rack bar 98 by a pin 98^A, and this block is also tiltingly secured by a pin 99 to a similar rack bar 100. The two bars 98 and 100 are mounted parallel to each other in a slideway bracket 101 that is adjustably secured in slots 102 that are formed in each end portion 50 of the bracket 44 by bolts 103, there being two sets of these corner wipers for each side corner of the box. Each toothed rack bar 98 is engaged by a gear 104 that is provided with side trunnions that are mounted in bearings that are formed in the sides of the slideway bracket 101. Each bracket 44 is provided with bearings 105 at its ends, in which are mounted square shafts 106, having round bushings which turn in the said bearings 105, and upon the respective shafts 106 are slidably mounted the gear wheels 104, two gear wheels being on each shaft. The gear wheels occupy the position shown in Fig. 7, or in other words, mesh with the toothed bars 98 when tight wrap boxes are passed through the machine, and for loose wrap boxes, the gears 104 are shifted to engage the toothed bars 100. The gears have short trunnions, one of which enters the opening in the adjacent side of the slideway bracket 101 when the gear is in mesh with 130

the toothed bar 98, while the other trunnion enters the opening in the other side of the bracket 101 when the gear is in mesh with the toothed bar 100. The slideway is formed 5 with a central partition web 107, which separates the toothed bars 98 and 100, the said web having a semi-circular recess to permit of the lateral shifting of the gear wheels 104. Upon the outer end of the partition web of each slideway is secured a 10 blade spring 108, having a curved portion which, when the gear wheel 104 is in mesh with either of the toothed bars 98 or 100 is adapted to bear upon the adjacent trunnion of the said gear wheel, and thus prevent lateral shifting of the same, as will be understood by reference to Fig. 7. Each 15 of the square shafts 106 is rotated by a gear 109 that is mounted on its forward 20 end and which is driven by a vertically disposed toothed rack portion that is formed on a bar 110 that is slidably mounted at its upper end in slideways 111 that are formed in the adjacent ends of the cross head 25 bracket 44. The lower end of this rack bar is adjustably secured to a vertically reciprocating cross head bracket 112. The 30 slots 113 in the lower end of the rack bar when it connects with the ends of the reciprocal cross head bracket permit of vertical adjustment of the rack bar.

The reciprocating bar 98 is moved by the vertical up-stroke of the cross head 112 and the vertical rack bar 110 and by its pinion 35 109 and the pinion 104, and the wiper 93 is thereby pressed against the corner of the blank and the corner of the box, which throw movement is sufficient to tiltingly compress the wiper against its abutment 40 spring as the wiper moves against and over the corner of the box against its adjacent corner and edges with sufficient resilient pressure to firmly glue the corners of the label to the corners of the box. After the 45 corner wiper has pressed the corner of the blank against the corner of the box, it is thrown back away from the box by the frictional engagement of the sliding bar 100, with its slideway, which acts to accomplish 50 this throw movement of the wiper in the following manner: The springs 97 normally hold the wipers 93 out of contact with the corners of the box, but the block 95 is slightly tilted on both its inward and outward movement by the frictional engagement of the tooth bar not operated by the gear 104 with its slideway. In the present instance the bar 98 is engaged by the gear 104, and the bar is moved outward or away 55 from the box. The pull on the bar by the gear wheel will cause the block to tilt outward or away from the corner of the box, owing to the consequent dragging movement of the bar 100, upon which an indirect pull 60 is exerted. Thus when the block 95 and its

wiper 93 start forward or toward the box, the wiper is thrown out slightly, but the initial movement of the bar 98 tilts the block 95, owing to the indirect pull of the bar 100, and consequently the wiper 93 is pressed 70 against the end of the box. The pinion thus causes the corner wiper to tilt against the box as the wiper starts across the end corner of the box, and the bar not operated by the gear 104 causes the wiper to tilt 75 away from the box after it has completed its corner label wrapping stroke. The reciprocating cross head 112 reciprocates the rack bar 110 that rotates the pinion and shaft that through the medium of the gear 104 reciprocates the bar 98 which moves the wipers to and from and across the surface of the corner ends of the box, at all four of its corners, and leaves the ends of the blank glued to the ends of the box. 80

The next step treatment and the final one of wrapping the blank around the bottom extension edges of the box and its flat ends is given by the end wipers which act simultaneously against the opposite ends of the blank and wrap them up against and glue them to the opposite ends of the box. Each of these end wipers comprises a tilting wiper supporting block 113, which is provided with a side lug 114 that is pivotally mounted on a pin 115, that extends through the ends of a yoke-shaped bracket 116. This yoke-shaped bracket stands in substantially a vertical position on the machine and it is provided with a flanged end portion 117 that 90 is bolted to a slideway block 118 that is adjustably secured to a slotted bar 119 that is slidably mounted in the table 4 of the frame of the machine. The lower end of the block 113 swings on its pivotal pin between the 95 arms of the yoke-shaped bracket, and during its operative movement it swings from a normal horizontal plane into a vertical plane. This wiper block supporting head comprises two parts or pieces, which act 100 independent of each other during the different stages of wrapping the end flaps against the opposite ends of the box. One of these parts is the block 113, which pivotally swings in the yoke-shaped bracket 115 116. The other part is the wiper head 120 and its supporting bar 121. This supporting bar 121 of the wiper head is reciprocally mounted in a slideway 122 formed in the block 118. 120

The wiper head projects beyond and over the slideway 122 of the block 113, and its underside is provided with a curved projection or fillet 123 that extends from the underside of the head to the adjacent side of 125 the bar.

This curved portion 123 of the head is engaged by a roller 124, that is rotatively mounted in the forked end of a vertically disposed rack bar 125, that is slidably 130

mounted in the bearing block 118, that is secured to the bar 119, the block 118 being provided with a partially inclosed and partially open slideway 126 in which the rack bar is supported. This rack bar is provided with a vertical row of gear teeth in line with the open space of the slideway 126.

This toothed rack portion of the rack bar 125 meshes with a pinion 127 that is mounted 10 loosely on a square shaft 128. The pinion is provided with a hub portion 129 that is adapted to be rotatively journaled in a bearing 130 in the block 118, there being one of these blocks 118 on each side of the center 15 of the machine on which the two extension end wrapping mechanisms are secured. The hub of the pinion extends through the bearing and an enlarged flange portion 131 is formed on it, which secures the pinion from 20 lateral movement in its bearing. The square shaft extends across the center of the table and on opposite sides of it far enough to allow these pinions and their bearings to be moved toward or away from the center of 25 the machine to wrap the opposite ends of the different sized blanks on their respective different sized boxes.

One end of this square shaft extends to 30 and through a bracket 132 that is secured to the adjacent side of the frame of the machine, and is journaled in a hub 133 that is formed on the bracket, and on its outer end a pinion gear 134 is secured that meshes with a vertically reciprocating rack bar 135, 35 which is slidably mounted in bearings 136 that are formed on a bracket 132, which is secured to the end of the table. The lower end of this rack bar 135 is connected to one 40 end of a reach bar 137, the opposite end of which is connected to the upper end of a forked lever 138, the opposite forked end of which straddles the main shaft. This lever is provided with a roller 139 that engages a cam 140 on the disk 10, which imparts a reciprocal movement to said rack bar, and rotates the pinion, which turns the square shaft and the pinions 127 that raise the rack bars 125.

The end wipers are adapted to effect extension lip wrap work by means of a spring 50 141 which is housed in a cup 142, which is bolted to a bracket 132. A rod 143 extends through this cup and its lower end is threaded and provided with nuts which 55 strike the bottom of the cup and define the stroke of the rod. The upper end of this rod engages the under edge of an arm 144 that is secured to the side of the rack bar 135. The spring 141 is an expansive tension 60 spring and its lower end rests against the bottom of the cup 142, while its upper end bears against a cap 145 that is slidably mounted in the cup and is secured to the rod 143.

65 The arrangement of the rack bar 135 with

respect to the reach bar 137, as shown in Fig. 1, is for wrapping ordinary boxes or such as are not provided with extension bottoms. The rack bar 135 is provided at its lower portion with a slot 146 and a block 70 147 is bolted to the upper end of the bar 137, and is provided with a recess in which rests the lower end of the rack bar 135, and the bar is held within the recess by a cap 148. A pin 149 passes through the lower end of the rack bar 135 and bears against the lower end of the block 147, and an adjustable block 150 bears against the upper end of the block 147, and is secured to the rack bar 135 by a bolt 151 which passes through 75 the slot 146. Thus arranged the cam fork 138, the reach bar 137, and the rack bar 135 move in unison, as will be understood, and with these parts thus arranged, as shown by Fig. 1, the end wipers are raised high enough to accomplish the end wiping of boxes of the greatest depth for which the machine is set. In wrapping boxes of less depth, however, the rack bar must have a shorter stroke in order to diminish the rotative travel of the gear wheels 127, and to accomplish this, the adjustable block 150 is 80 moved up a suitable distance above the block 147 and is firmly clamped to the rack bar by its bolt 151. Thus the movement of the cam 140 will raise the reach bar 137 a short distance before the block 147 engages the block 150, after which the rack bar and reach bar move up in unison. It is necessary however 85 that the rack bar should start to move upward simultaneously with the reach bar, and this is accomplished by the spring 141, which lifts the rod 143, the upper end of which engages and exerts an upward pressure against the projection 144, on the rack bar 135, by 90 which the pin 149 in the lower end of the rack bar is held in engagement with the block 147 of the reach bar, and the rack bar, through the action of the spring 141, moves up with the reach bar, until the nuts 152 100 on the end of the rod 143, engage the bottom of the housing 142, and the further action of the spring is thereby checked.

Assuming that the reciprocal stroke of the bar 135 has been properly adjusted to fit the 105 height of the ends of the box between the extension edge and the end wipers, then it rotates the pinion 134 and the cross bar and its pinions 127 which reciprocate the rack bars 125 of the opposite box end 110 120 wipers, and they cause each of these extension edge and end wrappers to act as follows:

The lower plunger block or form is of a size to extend to the outer edges of the side 125 and end extension bottom edges of the box. The guide block 113 is provided with a blank pressing blade 153 that is secured to it and that extends across its top and equally beyond its opposite sides and is of the full 130

width of the extension edge of the end of the box, and the wiper head is provided with a stepped portion on which a wiper block 154 is clamped by a clamping plate 155 that 5 is secured to the top of the head 120 by a clamping bolt 156. This wiper block has its upper edge rounded backward from its outside face, which with its rounded edge is covered with a pad of felt or other suitable 10 soft cushioning material.

This end wiper is of the full width of the box above its extension edge.

The bar 121 of the wiper supporting head is secured in its initial wiper starting position relative to the extension edge of the presser blade by a spring 157 that is secured to the back of the block 113 at one end, and extends beyond its lower end and fits with a resilient bearing pressure into a recess 158 15 that is formed in the bar 121. Consequently when the wiper head is down in the slide-way of the block and resting on top of the block, it and its bar are secured by this spring with a spring tension to the block, and 20 when in this position the wipers are ready to engage the opposite ends of the box the instant the extension edge blank turning and presser blades act operatively on the end flaps of the blanks, and the extension end 25 edges of the box, as will be presently described.

The lower end portion of the wiper head bar opposite the spring receiving groove is formed with a projecting lug 159, and the 30 toothed rack bar is provided with a recess 160 in its side that is arranged in the path of and to receive the lug, at a predetermined point in its upward movement, which point is reached in the upward movement of the 40 rack bar the instant the extension edge presser blades have completed their blank turning and wrapper movement over the edge and top side of the extension edge of the box.

45 At the instant the blades have been tilted down hard against the upper surface of the extension edge and the end wipers have been moved straight against the end surfaces of the box, the cam 8 operates mechanism to be presently described, which causes the blocks 154 to move slightly inwardly directly against the vertical end surfaces of the box. This inward movement of the end wipers against the ends of the box is accomplished in the following manner:

Each of the side bars 119 has a depending bifurcated lug 161, at its outer end, to which one end of a link 162 is pivotally secured, and the other ends of these links are connected to levers 163 and 164, which are rigidly secured upon shafts 165 and 166 respectively, which are mounted in the sides of the table. The lever 163 is a bell crank form of lever, and its other member is connected to the upper end of a rod 167, the

lower end of which has a collar 168 secured thereon; a coil spring 169 surrounds this end of the rod and bears against the collar 168, and the upper end of this spring bears against an eye bolt 170, which is secured in 70 the end of one arm 171, of a double armed lever, the other arm 172 of which carries a roller 173, which is adapted to be engaged by a cam on the peripheral edge of the cam disk 8. The double armed lever is mounted 75 on a stationary shaft 174, which projects from a bracket 175, that forms an integral part of the cap of the adjacent bearing standard 6. The shaft extends beyond the hub of the double armed lever and upon its outer end a collar 176 is rigidly secured. A coil spring 177 is mounted on the shaft between the collar and the hub of the double armed lever, one end of said spring entering a hole in the collar while its opposite end enters a hole in the hub of the lever, the spring being under a tension that will hold the roller 173 in contact with the periphery of the disk 8. The outer ends of the shafts 165 and 166 carry respectively 85 levers 178 and 179, the lever 178 extending upward, while the lever 179 extends downward, and the ends of these levers are connected by a rod 180.

Thus when the cam on the disk 8 passes 90 from under the roller 173, the spring 177 forces the double armed lever downward, and the rod 167 is drawn upon, and the shaft 165 is given a partial rotation by the bell crank 163, the other member of which draws 100 on the link 162 and moves the slotted bars 119 inward. Simultaneously the lever 178 on the outer end of the shaft 165 pushes on the rod 180, and the lever at its other end partially rotates the shaft 166, in an opposite direction to the shaft 165, and the lever 164 on the shaft 166, draws on its link 162, by which the other slotted plate 119 is moved inward. As the bars 119 carry the wiper 105 supporting blocks 118, it will be readily seen 110 that the said wipers will be moved toward each other against the ends of the box, and with a resilient contact effected by the spring 169. The eye bolt 170 on the reverse movement of the lever arm engages a collar 181, 115 which is pinned to the rod 167, and thus the rod is lifted, and the outward movement of the end wipers effected.

The opposite end of the shaft 166 from the lever 179 carries a stop finger 182 (see 120 Fig. 15), which when the wipers are moved to the desired point, or in contact with the ends of the box, strikes against the end of an adjustable screw 183, which is threaded to a lug on the side of the frame, and any 125 further movement of the lever arm 171 is against the spring 169, the wipers not being affected thereby.

The operation of our combined box bottom extension edge and end wiper blank 130

wrapping mechanism, is as follows: When the vertical rack bars 125 are moved upward by the rotative movement of the square shaft and the pinions 127, their rollers 5 which normally bear up under and against the curved projecting members 123 of the heads and their bars push these members upward and tiltly swing them at the opposite ends of the box supporting plungers up 10 over their pivotal pins 115, which movement moves the blades to engage the end flaps of the blanks and carry them over the outer edges of the extension edges of the ends of the box and carry them down against the 15 upper surface of the extension edges of the ends of the box and press them down tight up to and against the side corners of the extension edges, as these pressed blades are made wide enough and are arranged to fit 20 close and to press the blank against and glue them into the corners and against the adjacent ends of the box, for the thickness of these blades as they swing down against the ends and corners and the top surface of the 25 extension edge portion of the opposite ends of the box.

At the same time these extension edge wrapping blades swing over onto the top edges of the extension edge of the box, the 30 blank end flaps and the box end wipers 154 are also swung up over and they also engage the end flaps of the blank and carry it up against the ends of the box but they do not press hard enough at this time to prevent the 35 blades from pressing the end flaps of the blank down tightly against the top of the extension edge of the box. These presser blades are actuated by the vertical rack bars to press down hard against the top surfaces 40 of the extension edges, and this pressure forces them firmly against the lower plunger, upon which the extension edges of the box rest. Consequently the gummed blank is pressed and glued down tightly and 45 smoothly against the top and corner surfaces of the ends of the box. When the rollers 124 of the vertical rack bars have 50 swung the presser blades over and down firmly against the top surface of the extension edges of the ends of the box, they also 55 swingly tilt the outer ends of the blade supporting block down between the ends of the yokes to which they are pivotally secured, and against the sides of their respective rack bars, and the projecting lugs 159 of the bar extensions of the wipers supporting heads move into the recesses 160 of the rack bars, these several movements being formed quickly and automatically as the 60 rack bars move continuously upward, and they do not stop when the lugs swing into the recesses 160 of the rack bars as the pinions 127 and shaft 128 are rotating continuously, and consequently the instant the presser 65 blades have made their wrapping and press-

ing movement against the top of the extension edges, the next instant the rack bars are continuing their upward movement, and they lift the bars 121 up with them, and their rollers 124 engage and bear against 70 the outward curved projections of the head portions, and they crowd the wipers forward against the ends of the blank and press and glue them against the ends of the box, and at the same time the rack bars which are 75 still moving upward, lift the wiper bars and their heads and the wipers 154 with them and press as they move up the ends of the box, the end flaps of the blank up against and glue them to the ends of the box. The 80 rack bars then reverse their movement and move the wipers down first, then they move to throw the lugs out by striking against its top edge as they move down the instant the wiper head moves down against the top of 85 the block, which swingly tilts the wipers back into a horizontal position and completes the wrapping of the extension edges of the ends and also the ends of the box above its extension edge. Some of the extension edge folding elements of our present 90 invention are illustrated and described in our allowed application Serial Number 94,205, filed April 28, 1916. The ends of the side flaps and also the end flaps of the 95 blanks are left projecting far enough above the top ends of the box to allow them to be turned in by a special turn in mechanism, which we do not illustrate, but which is fully illustrated and described in our pending 100 application Serial Number 59,830, filed November 5, 1915, for an automatically operating multiple stage treatment box wrapping machine, and also in some of its features is claimed in our pending applications Serial 105 Numbers 122,054 and 122,061, both of which were filed September 25, 1916.

When it is desired to wrap the ends of straight sided non-extension edge boxes with blanks by either the tight or loose wrap kind 110 of box wrapping, the presser blades supporting blocks and the wiper heads and bars are removed with their yoke-shaped brackets from the machine. The rollers are also removed from the ends of the rack bars 125, 115 and the wiper head block and wipers are secured to them by pinning them between and to the yoke ends of the rack bars.

Our invention provides a simple and positively operating mechanism for wrapping 120 the ends of bottom extension edged boxes that act quickly and glues the end flaps of the blank neatly over the corner end flaps of the blanks that were previously wrapped around the side corners of the box and glued 125 to the ends of the box by the corner wipers; and while we have illustrated and described the preferred construction and arrangement 130 of our extension edge blank wrapping mechanism for the sides and especially for the 130

opposite ends of extension edge boxes, we do not wish to be limited to the construction and arrangement shown, as many changes might be made without departing from the 5 spirit of our invention.

Having described our invention, what we claim as new and desire to secure by Letters Patent, is:

1. An apparatus for wrapping extension edge boxes, said apparatus being embodied in a machine provided with an upper and a lower plunger arranged to receive, grip and move a blank and box between them, blank and box side and extension edge 15 presser blades and independently arranged side wipers surrounding said plungers, said side extension edge presser blades being arranged to wrap the side flaps of the blanks first to the opposite side extension edges of 20 the box and then to complete the wrapping of the side flaps of the box to its sides, and suitable corner wipers coöperating with said side wipers for wrapping the terminal ends of the side flaps of said blanks around 25 and to the opposite ends of said box, and extension end wipers comprising means including the pivotal swinging block and the reciprocal wiper head whereby the extension edges of the ends of the box are 30 wrapped over the terminal ends of said side flaps.

2. An apparatus for wrapping extension edge boxes, said apparatus being embodied in a machine provided with an upper and 35 a lower plunger arranged to receive, grip and move a blank and box between them, blank and box side and extension edge presser blades and independently arranged side wipers surrounding said plungers, said 40 side extension edge presser blades being arranged to wrap the side flaps of the blanks first to the opposite side extension edges of the box and then to complete the wrapping of the side flaps of the box to its sides, suitable 45 corner wipers coöperating with said side wipers for wrapping the terminal ends of the side flaps of said blanks around and to the opposite ends of said box, and means including a combined extension edge and 50 end wrapping mechanism comprising means including the swinging pivotal block, the reciprocating wiper head and the operating rack bar mechanism arranged to first wrap the end flaps of the blank to the opposite 55 ends of said box simultaneously and then to wrap the ends of the blank to the ends of the box above its extension edges.

3. In an extension edge box wrapping mechanism, the combination of the table frame and the blank and box supporting 60 plungers, with the side wipers comprising the brackets mounted on said table, the wiper block reciprocally mounted in said bracket, means including cam actuated gearing provided with a resiliently yielding 65 blank wiping stroke for reciprocating said wiper to and from said plungers, and means including a resiliently controlled tilting blade at the lower edge of said side wipers for exerting a combined longitudinal and 70 vertical blank wiping pressure of the lower edges of said side wipers, said blade being reciprocally actuated by said side wipers' reciprocating mechanism, and means whereby said extension edge wipers move first to 75 wrap the blank around said side extension edges, and then said side wipers are moved directly against the opposite sides of said blank and box.

4. In an extension edge box wrapping 80 mechanism, the combination with the table frame of the blank and box supporting plungers, with side wipers comprising the wiper block supporting brackets provided with a slideway, a rack bar plate slidably 85 mounted in said slideway, a blank wiping block secured in said plate in operative wiper relation to said blank and box and plungers, a toothed segment ended rock arm meshing with said rack bar, a reciprocating 90 rod secured to the free end of said rack bar by a resiliently yielding pivotal connection, means including a cam for reciprocating said rod, means including the corner wipers and the extension edge presser 95 blade for wrapping the blank around the sides and extension edges of the boxes, and means including the combined extension edge and end blank wrapping blades and their wipers arranged to be swingingly 100 moved together against the opposite ends of said boxes, and means for moving the end wipers upwardly to wrap the ends of the box after the extension edges have been 105 wrapped and while they are being held in a wrapped position.

In testimony whereof we affix our signatures in presence of two witnesses.
